UNITED STATES PATENT OFFICE.

JOHN ERDOSY, OF PHILADELPHIA, PENNSYLVANIA.

HOT-AIR AND VAPOR BATH DEVICE.

Application filed December 10, 1923, Serial No. 679,845.

To all whom it may concern:

Be it known that I, JOHN ERDOSY, a citizen of the United States, residing at Philadelphia, in the county of Philadelphia, and State of Pennsylvania, have invented certain new and useful Improvements in Hot-Air and Vapor Bath Devices, of which the following is a specification.

My invention relates to bath devices and 10 more especially to devices designed for use in taking hot air or vapor baths, and its objects are to provide a simple device adapted to confine the hot air or vapors and deflect them to all parts of the body and to 15 provide a device which may be quickly and easily set up or taken down, which occupies but little space when not in use, and to which access may be readily had.

These objects, and other advantageous 20 ends which will be described hereinafter, I attain in the following manner, reference being had to the accompanying drawings in which

Figure 1 is a plan view of a bath device 25 constructed in accordance with my invention,

Figure 2 a view similar to Figure 1 with the cover removed,

Figure 3 an enlarged section taken on line 30 3—3 of Figure 1,

Figure 4 an enlarged section on line 4—4 of Figure 3,

Figure 5 a perspective view of the supporting legs which form a part of my in- 35 vention,

Figure 6 an enlarged fragmentary plan view, partly in section, of the end connections, for the sides of the frame,

Figure 7 an enlarged fragmentary section 40 on line 7—7 of Figure 2, and

Figures 8 and 9 are perspective views of certain parts of my invention.

Referring to the drawings, 1 indicates a 45 collapsible supporting frame made in sections 2 and 3 connected to each other at their ends 4 and 5'. The connection includes a socket 6 in one section into which fits a pin 7 secured to the other section. Supporting legs 8 are pivoted to the sides 50 9 and 10 of the frame by T-heads 11 which loosely fit over the sections. The T-heads are secured to the legs in any suitable manner preferably as shown at 12. The lower ends of the legs may be provided with rubber pads 13. The legs are arranged in pairs and any desired number of pairs may

be used. I have found that a pair adjacent each end of the supporting frame is sufficient to firmly hold the frame in raised position. The legs of each pair are detachably connected by a pivot pin 14 held in place by a cotter pin 15.

A bed 16 is supported by the frame and consists of longitudinal strips 17 secured to the ends 4 and 5 of the frame, and transverse strips 18 interwoven with the longitudinal strips and secured to the sides 9 and 10 of the frame. The transverse strips are so disposed that the T-heads 11 will be between the transverse strips and thereby held against sliding movement on the sides 9 and 10. The transverse strips 18 are of such material as to yield sufficiently to allow disconnection of the sections 2 and 3 at their ends 4 and 5 when collapsing the frame.

A baffle sheet 19 is disposed under the bed and supported by the frame at 20. This baffle sheet prevents the hot air or vapors, coming from a heating device 21, from impinging directly against the body of a person on the bed, and deflects the vapors toward the ends and sides of the frame where they may pass upward between the strips 17 and 18 which form the bed. Spacers 22 of any suitable construction are secured to the baffle 19 in any manner for keeping the baffle sheet from being raised into engagement with the body of a person on the bed.

A cover 23 is composed of a framework 24 hinged at 25 and having secured thereto clips 26 which detachably support spans 27. A covering 28 rests on spans 27 and is secured to framework 24 in any suitable manner. The covering is provided with a cut-out part 29 through which the head of the user may extend. This cut-out part is partially closed by an elastic sheet 30 which is adapted to engage the body of a person and prevent the hot air or vapors from escaping. This cover 23 rests on frame 1, encloses the upper part of bed 16, and is held to the frame by springs 31 connected to the spans at 32 and to connecting parts such as eyes or hooks 33 secured to the T-heads. These springs 31 may be readily connected or disconnected from the spans or the eyes.

A casing 34 is supported by frame 1 in any suitable manner, preferably by providing snap fasteners 35 on the strips 17 and 18 and on the upper edge 36 of the casing.

The lower edge 37 engages the floor or ground on which the legs stand, and thus prevent the hot air or vapors from escaping. The casing thus encloses the lower part of the bed and confines the hot air or vapors so that they will contact with the body of the user.

To use my device, the head-part of cover 23 is raised on hinge 25 into the position shown in dot-and-dash lines so that the user may get under the cover and lie on the bed. The cover is then lowered into the full line position and springs 31 at the head-end of the frame are hooked to eyes 33 and spans 27. The elastic sheet 30 will then engage the bdy of the person near the neck. The device is then in position for use. If the air or vapor is too hot, opening 38 may be opened by door 39 to allow some to escape. After the bath, springs 31 are unhooked from eyes 33 and the head part of the cover raised into the dot-and-dash line position to permit the user to get from under the cover.

To take down the device, springs 31 are unhooked from the eyes 33, and spans 27 are lifted out of clips 26 to allow the covering 28 to collapse within framework 24. This cover 23 may rest on the bed in this collapsed position. The casing 24 is then unhooked from the fasteners 35 and folded in any suitable manner and placed on the collapsed cover 23. Pins 14 are removed from legs 8 by taking out cotter pin 15. The legs may be swung against baffle sheet 19 and the device put away in small space. If desired the pins 14 may remain in legs 8 to keep them pivotally connected and the sections 9 and 10 pulled apart slightly so that the pins 7 will come out of sockets 6, after which the sections may be swung together on the pivoted legs 8. In each case the device may be collapsed into a very small space.

By constructing the bath device as above set forth it may be used for camps or out of doors and will take little space in transportation.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what

I claim as new and desire to secure by Letters Patent is:—

1. A bath device including a supporting frame; a bed supported by the frame; a baffle, supported by the frame, disposed under the bed; spacers between the bed and the baffle; a cover, supported by the frame, enclosing the upper part of the bed, and a casing, supported by the frame, enclosing the lower part of the bed.

2. A bath device including a supporting frame made in sections, each section being provided with a socket on one end and a pin on the other end, the pin on one section being adapted to fit within the socket in the other section; a bed supported by the sections; a cover, supported by the sections, enclosing the upper part of the bed, and a casing supported by the sections, enclosing the lower part of the bed.

3. A bath device including a supporting frame made in sections; means detachably connecting the sections; T-heads pivoted to the sections; legs secured to the T-heads and pivotally connected to each other; connecting parts on the heads; a bed supported by the frame; a cover, supported by the frame, enclosing the upper part of the bed; means connecting the cover with the connecting parts, and a casing, supported by the frame, enclosing the lower part of the bed.

4. A bath device including a supporting frame; longitudinal strips secured to the ends of the frame; transverse strips secured to the sides of the frame and interwoven with the longitudinal strips; a cover, supported by the frame, enclosing the upper part of the strips, and a casing, supported by the frame, enclosing the lower part of the strips.

5. A bath device including a supporting frame; longitudinal strips secured to the ends of the frame; transverse strips secured to the sides of the frame and interwoven with the longitudinal strips; legs pivoted to the frame between the transverse strips and connected with each other; a cover, supported by the frame, enclosing the upper part of the strips, and a casing, supported by the frame, enclosing the lower part of the strips.

In testimony whereof I have signed my name to this specification in the presence of two subscribing witnesses.

JOHN ERDOSY.
